UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

SELF-ALIGNING VALVE.

Application filed October 4, 1921, Serial No. 505,221. Renewed January 6, 1926.

This invention relates to an atomizing valve and particularly to a valve which is used in connection with internal combustion engines as a fuel injection valve. Such valve constructions normally must include a valve head and a seat upon which the valve head is seated. The relation of these two must be such that complete closure of the valve takes place. When the valve is open the valve head may be entirely out of contact with the seat, possibly lying centrally with respect thereto, or it may rest against one side of the seat, and this latter condition is the least desirable. When the valve is mechanically guided, the possibility of having the valve head rest against one side of the seat while it is open and bear unevenly at closure depends upon the degree of accuracy of machining and assembling the parts. Since such injection valves are generally comparatively small in size, this problem is always acute, although it is to some extent capable of mechanical solution. When, however, the size of the valve opening is reduced, errors in guiding bear more and more important relation to the size of the opening and tend increasingly to produce poor closures and ununiform and otherwise unsatisfactory sprays. Where the valve is mechanically guided at the time of seating two restraints are imposed upon the movement of the valve head, namely that caused by the mechanical guiding, and that caused by contact with the valve seat, and unless these two restraints tend along the same line poor closure, uneven wear, and unsatisfactory atomization are inevitable. As the size of the valve opening is decreased, a point is reached beyond which satisfactory mechanical guiding is impossible. I have discovered that the parts may be made self aligning, and that such an arrangement is of advantage with valves of all dimensions and essential with valves having very minute atomizing openings. My invention therefore has for one object to produce a self aligning valve in which the mounting and arrangement of the parts forming the valve opening is such that they tend automatically to assume proper relative positions.

With the self aligning valve of this invention the valve head is at the time of closing under the single restraint of the valve seat, and it is therefore certain properly to

locate itself within the valve seat so as to 55 cause complete closure and uniform pressure upon the valve seat which makes for uniform wear upon the parts. When the valve is open, the valve head is under the influence only of the liquid flowing through the open 60 seat and is not positively held in any fixed position which with a poor guide might be held against one side of the seat. Since there is no restraint other than that of the liquid, the valve head tends to produce an 65 opening around the entire periphery of the valve and may assume any position within the limits of the seat, though it might not lie absolutely centrally.

The construction of my invention avoids 70 the necessity of close limits in the machining of the valve parts and particular care or accuracy in the assembling.

The invention is illustrated more or less 75 diagrammatically in the accompanying drawings, wherein:

The figure shows a vertical cross section of my valve throughout.

Like parts are designated by like characters throughout.

A is a valve housing having a longitudinal passage A' therein. A² is a sleeve, screw threaded in the valve housing having a passage A⁴ in line with a passage A⁵ which in turn communicates with the passage A'. A⁶ is a fluid supply pipe communicating with the passage A⁴ and connected up with the sleeve A² by the coupling A⁷.

B is a cap, screw threaded on the discharge end of the valve housing. The housing is itself screw threaded in the wall B' of an engine cylinder or the pressure chamber or any other suitable apparatus where this valve might be appropriately positioned. The end of the valve housing is counter-sunk as at B². B³ is a packing washer arranged within the counter-sunk end about its periphery. B⁴ is a spray disc apertured as at B⁵ and the aperture is adapted to be closed by a blunt plug or needle valve B⁶ on the end of the valve stem B⁷. The stem is enlarged at its upper end, surrounded by a packing B⁸ and compressed by a gland B⁹. The end of the valve stem is screw threaded as at B¹⁰ and a hand wheel B¹¹ has a screw threaded engagement therewith being held against longitudinal displacement on the yoke B¹².

so that the manipulation of the hand wheel may move the plug or needle valve toward or from the spray disc.

While I have shown an operative invention, still it will be obvious that many changes in form, shape and relation of parts may be made without departing materially from the spirit of my invention, and I wish therefore that my showing be taken as in 10 a sense diagrammatical. In particular, although I have here shown the valve stem as movable and the valve seat as substantially stationary, so far as lateral movement is concerned, the conditions might be reversed 15 and the valve seat itself might be mounted so as to be self aligning with relation to a rigidly held valve stem.

While in the form shown the valve head is flexibly and movably mounted, the valve 20 head might be held rigidly and the valve disc might be movable so as to be self aligning with relation to the head, and either of these constructions is within the contemplation of my invention and I do not wish to 25 be limited to the form shown.

The valve of the form shown is adapted to be opened by hydraulic pressure from within which deflects the disc until it is out of contact with the valve head. My idea 30 of the self aligning valve might, however, be applied to a mechanically opening valve, and this would be true whether the valve is opened by mechanical movement of the valve head or the valve seat.

35 The use and operation of my invention are as follows:

The stem carrying the needle point or valve head as here shown is made relatively small in diameter in comparison to its 40 length, with the object of obtaining considerable flexibility, and the needle tip or valve head is given generous clearance in the valve bore. No attempt is made accurately to position the discs or locate the 45 seat, whether in the disc itself or in the inserted seat plug. In the construction shown very generous leeway is permitted.

This construction permits the needle, if

the general location of the parts is accurate to within an amount not greater than the 50 diameter of the hole to align itself within the hole. If the point finds the hole at all when being moved downward into position, it will pass into the hole with relative freedom and locate itself on the seat centrally 55 with satisfactorily uniform pressure on all sides.

I claim:

1. In an atomizing valve two orifice forming members, the support for one being rigidly fixed, the support for the other being rigidly fixed at its base, and due to its own elasticity adapted to be flexed laterally and in the normal operation of the valve held against axial movement, the two 35 members adapted to have relative movement in response to hydraulic pressure to form an atomizing orifice.

2. In an atomizing valve two orifice forming members, the support for one being rigidly fixed, the support for the other being rigidly fixed at its base, and due to its own elasticity adapted to be flexed laterally and thereby being self centering, and in the normal operation of the valve held 70 against axial movement, the two members adapted to have relative movement in response to hydraulic pressure to form an atomizing orifice.

3. In an atomizing valve a perforated 80 spring disc rigidly supported and a co-operating needle valve member adapted to close the perforation in said disc, the support for said valve member being rigidly fixed at its base, and due to its own elasticity adapted to be flexed laterally, and in the normal operation of the valve held against axial movement, the disc adapted to move away from the needle in response to hydraulic pressure to form the atomizing orifice.

Signed at Chicago, county of Cook and State of Illinois, this 22nd day of September, 1921.

PHILIP LANE SCOTT.
